ISAAC DINGEE, OF CHARLESTOWN, AND EDWARD T. SMITH, OF BOSTON, MASSACHUSETTS.

HAT-MACHINE.

Specification of Letters Patent.

Patented Feb. 8, 1916.

1,171,106.

Application filed August 11, 1915. Serial No. 44,920.

To all whom it may concern:

Be it known that we, ISAAC DINGEE and EDWARD T. SMITH, respectively of Charlestown and Boston, in the county of Suffolk and State of Massachusetts, have invented 5 certain new and useful Improvements in Hat-Machines, of which the following is a specification.

This invention relates to the manufacture 10 of hats, and refers particularly to the shaping of the bodies of hats upon blocks.

The object of our invention is to provide 15 a simple and easily operated machine which, by the employment of a heated fluid medium will transmit equal and uniform pressure to all portions of a hat body upon a block, which pressure can be varied or regulated 20 at the will of the operator, and then instantly relieved. We accomplish this object by means which prevent any access of 25 the fluid medium to the fabric or material of the hat body, thus avoiding any liability of injuring it.

A further object of the invention is to 30 provide a machine which pulls, blocks, and presses the hat body, all at one operation.

With these and other objects in view, our invention consists in the improvements 35 which we will now proceed to describe and claim.

Of the accompanying drawings which illustrate one embodiment of our invention: Figure 1 is a front elevation of the machine, with the operating foot lever or 40 treadle in section, and the base of the frame omitted. Fig. 2 is a side elevation. Fig. 3 represents a vertical section. Fig. 4 is a view similar to a portion of Fig. 3, but with the illustrated parts in the relative positions 45 which they occupy during the exertion of final blocking pressure.

Similar reference characters indicate similar parts in all of the views.

A suitable lower framework 12 supports 45 a table 13, the latter having uprights or struts 14 which support a top bar 15 the purpose of which is to guide the upper portions of the vertically sliding rods, and to provide supports for pulleys, all as herein- 50 after described.

Mounted on the table 13 is a fluid container 16 which may be briefly termed a pot. Its walls are strong, and it is heated by any suitable means, such as by steam pipes 17 55 (Fig. 3) communicating with a space below

a false bottom 18. In practice, this pot is filled with an elastic medium that will conduct heat, such as a compound of tar and powdered carbon, and it is then covered by an elastic sheet 19 (preferably rubber) 60 which constitutes the former to cause the hat material to conform to the block. The sheet is removably held in place by having its margin bent down over the rim of the pot and secured by a clamping ring or 65 band 20.

Communicating freely with the interior of the pot are one, two or more expandible and contractible chambers for the fluid. We illustrate two, each consisting of a cylinder 21 containing a piston 22, (see dotted lines, Figs. 1 and 2) and connected by a large elbow pipe 23 with the pot. The piston rods 24 of the two pistons extend through the lower ends of the cylinders, and 75 their lower ends contact with arms 25 of a rock shaft 26 which has another arm or lever 27 of any requisite length on which a weight 28 is mounted to be adjusted to vary the effective resistance, furnished by said 80 weight, to the passage of the fluid from the pot into the cylinders.

Two pairs of vertical slide rods 29 are mounted in guide bearings 30, 31, projecting 85 from the frame 12, and are guided at their upper ends in openings in the top bar 15. Said rods carry a cross head 32 secured to their upper portions as by screws 33. Counterweights 34 are connected to said cross heads by cords or chains 35 running 90 over pulleys 36 mounted on the top bar 15. The lower ends of the slide rods are connected by a cross piece 37, portions of which pass between vertical guide bars 38 extending from the table 13 down to the base of 95 framework 12. A foot lever or treadle 39, pivoted at 40, is connected by a link 41 with the cross piece 37. Suitable means are employed to enable the treadle to be held down for the purpose hereinafter described, such 100 means as illustrated, comprising a tooth 42 projecting from the treadle and adapted to be caused to engage either one of a series of notches forming a rack 43 carried by one of the bars 38. Depression of the treadle 105 brings down the cross head 32 to which the hat block 44 is connected by suitable coupling devices not necessary to illustrate.

Between the hat block and the pot 16 is a vertically movable support 45 for the sheet 110

of hat material α . For convenience, we term this support the carrier. It is ring shaped in that it has a circular or oval opening, and is supported by a plate 46 which moves vertically on the rods 29. It is suspended from the cross head 32 by straps 47 or other suitable connections that will determine the maximum distance between the cross head and carrier but will permit the cross head to contact with the carrier when moving down. To hold the carrier normally in the position shown in Fig. 1, suitable means are employed such as struts 48 rising from the table 13 and having detents or supporting lugs 49 for the marginal portions of plate 46. The under sides of the lugs are beveled. The struts are of material that will permit them to yield slightly outwardly. Their upper ends extend above the plate 46 and are provided with cam portions 50 adapted to be acted upon by rolls or lugs 51 of the cross head 32 when the latter descends, to flex the struts outwardly to release the detents 49 from plate 46.

25 The pot 16 may have a suitable valve-controlled vent 52 as indicated in Fig. 4 by means of which air, or gas, may be permitted to escape, if such should gain access to, or accumulate in, the pot.

30 In operation, with the parts in the position indicated in Figs. 1, 2 and 3, and with the desired hat block 44 in place, the operator places a sheet of the material which is to be pulled and pressed or blocked, upon the carrier 45, and if desirable, holds it under tension across the opening while depressing the treadle 39. This lowers the cross head 32 and the block and as the latter contacts with the material α begins to pull it and finally draws it down more or less snugly over the block. When the rolls or lugs 51 reach and act on the cams 50 to push the struts out and release the plate 46, both the cross head (and the block) and the carrier move down together. If desired, suitable friction may exist between the plate 46 and the rods 29 to prevent the plate 46 from descending faster than the cross head. As these parts continue to descend, and the block with its covering of hat material α begins to stretch the elastic sheet former 19, the heated fluid in the pot is displaced into the cylinder 21 against the resistance afforded by the weight 28. When the block reaches the position indicated in Fig. 4, or as near such position as the shape and character of the block render desirable, the treadle 39 is held by engaging its tooth 42 with the rack 43 and is then left for the desired length of time while the heated fluid, under pressure as stated, acts on the material α to press or block it. Then the treadle is released and the counterweights 34 cause the cross head and block to rise. When the straps 47 draw taut, the continued rise of

the cross head lifts the plate 46 and as the edges of the latter pass the inclined faces of the lugs 49 of the struts 48, the latter are flexed until the said lugs reengage the plate to hold it in position for the next operation. 70 Of course when the block rises from the position shown in Fig. 4, the fluid that had been displaced is returned to the pot by the action of pistons 22, under the influence of weight 28. During the pressing and blocking operation, the degree of pressure can be increased beyond that for which the weight is adjusted along arm or lever 27, by manually depressing said lever. 75

Having now described our invention, we claim:

1. A hat machine comprising a receptacle for fluid, a yielding cover or diaphragm therefor, means for forcing a block and hat material against said cover to depress the latter, means for permitting the fluid to be displaced, and means for causing back pressure on the displaced fluid.

2. A hat machine comprising a receptacle for fluid, a yielding cover or diaphragm therefor, means for forcing a block and hat material against said cover to depress the latter, means for permitting the fluid to be displaced, and means for causing back pressure on the displaced fluid, means being provided for heating the fluid.

3. A hat machine comprising a receptacle for fluid having means for heating the fluid, an elastic cover for the receptacle, means for holding the fluid under pressure while permitting it to be displaced, means for causing a block and hat material to flex the said cover and displace the fluid, and means for variably determining the pressing action of said cover caused by said fluid.

4. A hat machine comprising a receptacle for fluid having means for heating the fluid, an elastic cover for the receptacle, means for holding the fluid under pressure while permitting it to be displaced, a carrier for 110 hat material movable toward and from the receptacle, and means for moving a block to said carrier and then with the carrier to the receptacle.

5. A hat machine comprising a fluid container having a flexible cover, means for forcing a hat block with applied hat material below the plane of the top of the container, means for permitting the fluid in the container to be displaced, and means for applying variably determined resistance to displacement of the fluid.

6. A hat machine comprising a fluid receptacle having an expansible and contractible chamber connected therewith, means for forcing a hat block with applied hat material into said receptacle, means for variably resisting expansion of said chamber, and means for preventing access of fluid in the receptacle to the said hat material.

7. A hat machine comprising a fluid container having a flexible cover, means for forcing a hat block with applied hat material below the plane of the top of the container, a cylinder communicating with the interior of the container, a piston in said cylinder, and means for opposing movement of the piston.
8. A hat machine comprising a fluid container having a flexible cover, means for forcing a hat block with applied hat material below the plane of the top of the container, a pair of cylinders communicating with the interior of the container, piston tons in said cylinders having piston rods and a rock shaft having a weighted arm or lever and having arms against which the piston rods bear.
9. A hat machine comprising a fluid container having a flexible cover and provided with means for permitting the cover to yield and the fluid to be displaced, means for causing back pressure on the displaced fluid, slide rods, a cross head connected to the slide rods and having means for carrying an inverted hat block, and manually controlled means for lowering the slide rods and cross head.
10. A hat machine comprising a fluid container having a flexible cover and provided with means for permitting the cover to yield and the fluid to be displaced, slide rods, a cross head connected to the slide rods and having means for carrying an inverted hat block, a movable carrier for hat material between said cross head and flexible cover, and a foot lever or treadle connected to said slide rods.
11. A hat machine comprising a fluid container having a flexible cover and provided with means for permitting the cover to yield and the fluid to be displaced, slide rods, a cross head connected to the slide rods and having means for carrying an inverted hat block, a movable carrier for hat material between said cross head and flexible cover, and a foot lever or treadle connected to said slide rods, means being provided for locking the said lever and the parts operated thereby, in lowered position.
12. A hat machine comprising a receptacle for fluid, a yielding cover or diaphragm
- therefor, means for forcing a block and hat material against said cover to depress the latter, means for permitting the fluid to be displaced, means for causing back pressure on the displaced fluid, and means for locking the parts to hold the block and hat material in position for continued pressure.
13. A hat machine comprising a vertically movable hat block, a support or carrier for hat material below the hat block and normally spaced therefrom, a fluid container having a flexible cover below said carrier, and means for lowering the hat block to the carrier and then lowering both to cause the block and applied material to depress the said flexible cover into fluid in the container.
14. A hat machine comprising a vertically movable hat block, a support or carrier for hat material below the hat block and normally spaced therefrom, a fluid container having a flexible cover below said carrier, and means for lowering the hat block to the carrier and then lowering both to cause the block and applied material to depress the said flexible cover into fluid in the container, means being provided whereby, when the hat block is raised to normal position, the said support or carrier is also lifted to normal position.
15. A hat machine comprising a vertically movable cross head and a hat block carried thereby, a support or carrier for hat material below the cross head and normally spaced therefrom, a fluid container having a flexible cover below the material carrier, means for sustaining said carrier in normal position, means for lowering the cross head to said carrier, means for automatically releasing the carrier when the cross head reaches it whereby both the hat block and the hat material applied thereto may be depressed below the plane of the top of the fluid container, means for causing the cross head to lift the carrier to normal position when the cross head rises, and means for causing the carrier sustaining means to be automatically held when lifted.

In testimony whereof we have affixed our signatures.

ISAAC DINGEE.
EDWARD T. SMITH.
